United States Patent Office

Des. 186,060
Patented Sept. 1, 1959

186,060

DISPLAY STAND

Harvey H. Udesky, Skokie, and Alan R. Segal, Chicago, Ill., assignors to The Evron Company, Chicago, Ill.,
a corporation of Illinois

Application January 12, 1959, Serial No. 54,142

Term of patent 14 years

(Cl. D80—9)

Figure 1 is a perspective view of a display stand showing our new design.

Fig. 2 is a side elevation thereof.

Our design for the display stand disclosed is characterized by the particular ornament at the top of the center standard in association with the uniformly spaced, circular shelves and base, all as shown.

We claim:

The ornamental design for a display stand, as shown and described.
